[57] CLAIM

The ornamental design for a drum case, substantially as shown and described.

DESCRIPTION

FIG. 1 is a top plan view of a drum case showing my new design;

FIG. 2 is a front elevational view, a fragmentary section being broken away and omitted to show the contour of the cover portion;

FIG. 3 is a side elevational view, a fragmentary section of the cover being broken away to show the contour thereof; and

FIG. 4 is a bottom plan view.

Fig. 1.

Fig. 2.

Fig. 3.

Fig. 4.
